UNITED STATES PATENT OFFICE.

LEONARD ATWOOD, OF PHILADELPHIA, PENNSYLVANIA.

CRANE.

SPECIFICATION forming part of Letters Patent No. 498,605, dated May 30, 1893.

Application filed March 20, 1890. Serial No. 344,665. (No model.)

To all whom it may concern:

Be it known that I, LEONARD ATWOOD, a citizen of the United States, and a resident of Philadelphia, Pennsylvania, have invented 5 certain Improvements in Cranes, of which the following is a specification.

My invention relates to certain improvements in hydraulic cranes and has for its object the construction of a crane which may be 10 operated by a pump contained within its base and forming a self contained structure; the pump being driven preferably by an independent motor, such as an electric motor, as more fully set forth hereinafter.

15 In the accompanying drawings:—Figure 1 is an elevation of my improved crane, a portion of the standard being cut away. Fig. 2, is a vertical section of the same on the line 3 4, Fig. 1. Fig. 3, is a sectional plan view on the line 1—2, Fig. 2, on a somewhat larger scale. Fig. 4, is a vertical section on the line 5—6, Fig. 3. Fig. 5, is a vertical section on the line 7—8, Fig. 3. Figs. 6 and 7, are views showing the controlling valve in different positions.

25 A is the base of the crane to which is secured a vertical hollow standard B having at its upper end a suitable cap B' by which it may be secured to the roof or supporting beam 30 of a building; the hollow standard being utilized as a reservoir for the fluid by which the crane is operated.

Secured to the standard B is a piston b provided with suitable packing and fitting over 35 the piston and the standard B is a movable cylinder D preferably open at its lower end and suitably packed at its upper end to prevent the escape of fluid between the head of the cylinder and the standard. On the exterior of the cylinder are pins d, d, on which are mounted tie bars E, E, secured at their upper and lower ends respectively to collars E', E' 40 adapted to slide upon the standard B above and below the cylinder; secured to the collar E', as shown in Fig. 1, is a horizontal crane arm F; the object of this construction being to prevent the binding of the cylinder upon the standard when a load is being raised.

In the base A of the structure is a pump 45 cylinder A' preferably formed integral with the base casting; and in any suitable bearings, preferably in the cylinder heads a, a' is

mounted a shaft G carrying a piston H provided with radial slots h for the sliding piston blades g. The pump is driven in the present instance from an electric motor, the shaft 55 I' of which is connected to the shaft G of the pump, through the pinion i and gear wheel i'. By using an electric motor to drive the pump I dispense entirely with line shafting and 60 with piping, using simply the ordinary current conducting wires.

The inlet j for the pump connects with the interior of the standard B which forms a reservoir from which the pump is supplied, and 65 the outlet passage k from the pump communicates with a transverse passage k' in the base A. The fluid from the pump passes out through the passage k, into and through the passages k', l, l', through the ports of the 70 regulating valve m, and thence through the passage m' to the vertical pipe n which communicates with the space in the cylinder between the head and the piston, so that the fluid as it is forced by the pump from the reservoir will pass into the cylinder and raise it 75 when the controlling valve m is in the position shown in Fig. 5.

The controlling valve m is provided with a suitable operating handle m² and when it is 80 desired to lower the crane arm and cylinder the valve is turned to the position shown in Fig. 7, the fluid passing out through the pipe n, the passage m', the ports of the valve m, the passage p, the pipe p' to the opposite side 85 of the base A; through the passages q, q' to the passage j and thence into the reservoir B.

To maintain the cylinder in an elevated position the controlling valve m is turned to the position shown in Fig. 6, confining the fluid 90 in the cylinder, the pipe n and the passage n'. The fluid as it is forced by the pump passing through the passage k, the passages k', l', p, p' and q to the inlet side of the pump, so that the motor can be run continuously while the 95 load is suspended. When the pressure in the pump exceeds the pressure to lift the load, or the valve m has been so turned as to cut off the passage l', I provide a by-pass, preferably by a pipe s communicating at its opposite 100 ends with the passages k and q and having therein a valve S normally closed by the pressure of a spring s' of sufficient strength to keep the valve closed under ordinary pressures, but

so arranged that when the pressure exceeds a certain predetermined limit the valve will open and the excess of fluid passes through the pipe *s* to the passage *q* which communicates with the opposite side of the pump cylinder.

In some instances the reservoir may be independent of the standard, but is preferably in close proximity to the crane or situated on the crane, as shown for instance by dotted lines in Fig. 2.

I claim as my invention—

1. The combination of the fixed standard, a piston thereon, a movable cylinder mounted on said standard, sliding collars on the standard above and below the cylinder, vertical tie bars connecting the cylinder to the collars, a crane arm projecting from the upper collar, and a supporting strut for said crane arm carried by the lower collar, substantially as specified.

2. The combination in a crane, of the standard, a piston thereon, a cylinder adapted to slide on said standard and piston, centrally located pins on said cylinder, vertical bars *E* on said pins, collars *E'* *E''* also connected to said tie bars, with a crane arm carried by the collars, substantially as specified.

3. The combination of the base, the pump therein, a standard, a reservoir therein, a piston secured to the standard, an open ended cylinder sliding on said piston, guiding collars connected to the cylinder and adapted to slide upon the standard, and a pipe extending within the standard and communicating with the pump and with the interior of the cylinder at a point above the piston, substantially as specified.

4. The combination of the base *A*, a reservoir *B*, a cylinder *D*, a rotary pump in said base, passage *j* forming communication between the reservoir and the pump, passages *k*, *k'*, *l*, *l'*, and *m'*, and a pipe *n*, forming a communication between the pump and the cylinder *D*, a controlling valve *m*, and a by-pass *p*, communicating with the passage *q*, leading to the inlet side of the pump, substantially as specified.

In testimony whereof I have signed my name to this specification in the presence of two subscribing witnesses.

LEONARD ATWOOD.
